Patented Oct. 22, 1918.

FIG. 1.

FIG. 2.

FIG. 4.

FIG. 3.

Albert E. DOMAN ^{INVENTOR}
BY Howard P. Garrison
ATTORNEY.

UNITED STATES PATENT OFFICE.

ALBERT E. DOMAN, OF ELBRIDGE, NEW YORK, ASSIGNOR, BY MESNE ASSIGNMENTS, TO DYNETO ELECTRIC CORPORATION, OF SYRACUSE, NEW YORK, A CORPORATION OF NEW YORK.

MANUFACTURE OF COMMUTATORS.

1,282,051.

Specification of Letters Patent. Patented Oct. 22, 1918.

Application filed December 26, 1916. Serial No. 138,971.

To all whom it may concern:

Be it known that I, ALBERT E. DOMAN, a citizen of the United States of America, and resident of Elbridge, in the county of 5 Onondaga, in the State of New York, have invented new and useful Improvements in the Manufacture of Commutators, of which the following, taken in connection with the accompanying drawings, is a full, clear, and 10 exact description.

This invention relates to certain improvements in the manufacture of commutators and parts thereof and in the blank from which the bars or segments thereof are made.

15 The primary object of the invention is to reduce the expense of raw materials, as copper, and the cost of manufacture by forming the raw materials preferably in long, cold drawn strips tapered laterally from a central portion or formed with a double bevel so that the bars, with suitable integral tangs, may be punched from the strips with but slight waste of material, the angle or bevel of the strip being of such degree as to correspond with a required angle when a predetermined number of bars or segments are to be nested together to form a complete cylinder.

Other objects and advantages will appear 30 from the following description taken in connection with the accompanying drawings, in which—

Figure 1 is a view of the blank of this invention from which the commutator bars or 35 segments may be punched.

Fig. 2 is a top plan view of the blank, the shape of the bars and the method of punching being indicated.

Fig. 3 is a view of a complete bar or segment.

Fig. 4 is a cross section of a commutator as constructed from such segments.

The invention, as shown, comprises the blank —1— which may preferably be a relatively long, cold drawn strip of suitable material, as copper, having a central substantially plane horizontal portion —2— with side portions —3— and —4— tapered or beveled in opposite directions therefrom. 45 Both sides of the blank are symmetrical and of the same conformation.

The side portions —3— and —4— are disposed at the same angle relatively to the portion —1— and are of equal width, the angle 55 of disposition of the outwardly converging

portion —3— or the outwardly converging portion —4— being of such a degree as is required in the manufacture of a complete cylinder from a predetermined number of similarly shaped nested bars or segments. 60 With a commutator constructed of thirty-three bars or segments as here illustrated, the angle of disposition of the outwardly converging side portions —4— or the outwardly converging side portions —3— is approximately 10°, 54', 32", the angle of disposition of each beveled portion —4— or each beveled portion —3— and the central portion —2— being approximately one-half the angle last described. The angular disposition will, of course, vary in accordance 70 with the number of segments to be used in forming a complete cylinder.

The strip —1— is of a width equal to the complete width of the commutator bar —5— 75 including the tang —6— for electrical connections and is twice the width of the body —7— of the commutator bar adapted to form the cylindrical portion of the commutator.

From the strip —1— commutator bars —5— can be punched or cut with a minimum waste of material and with a minimum cost of production in the manner shown in Fig. 2. The bar is punched along lines 8, 9 and 10, 85 the line 8 extending from one side of the bar to the central portion of the bar, said line being spaced from the adjacent end of the strip —1— a distance equal to the desired width of tang —6—. The line 9 extends from the inner termination of line 8 longitudinally and centrally of the strip —1— a distance equal to the desired width 90 of the body of the commutator bar adapted to form the cylindrical portion of the commutator. The line 10 extends from the termination of line 9 to the edge of the bar opposite that at which the line 8 terminates.

Preferably portions —13— and —14— are cut from the edge of the bar to form, in connection with body —7—, an integral wedge-shaped member —11— adapted to receive suitable, usual and well known means, as ring members, for holding the segments in nested position in the completed commutator. These portions —13— and —14— which are cut out to form the wedge-shaped member —11— are the only waste material in constructing the commutator bars.

In order to form the second commutator 110

bar, the strip is punched along line 12 and the portions —13— and —14— are preferably punched out to form the wedge-shaped member —11—. The line 12 is spaced from the line 10 a distance equal to the desired width of tang —6—. By this method of cutting or punching, two complete commutator bars are cut from a strip of material equal in width to the radial length of a commutator bar and equal in length to the complete width of a commutator bar plus the width of one tang.

The bars, as shown, may be mounted upon a suitable sleeve or core —15— and may be held in assembled position upon the sleeve in any suitable and usual manner.

Although I have shown and described one particular construction and exact method as constituting a preferred embodiment of this invention, it will be apparent that changes and alterations may be made in the exact form of the commutator bar and the exact method of punching the same without departing from the spirit of this invention as set forth in the appended claims.

What I claim is:—

1. The method of manufacturing commutator bars consisting in forming suitable material into a relatively thin wide strip tapering from a central portion toward opposite edges, cutting the bar at substantially right angles to its length from a predetermined edge to substantially the central portion of the bar and along a line located at a distance from the end of the bar substantially equal to the width of the tang of the commutator bar to be produced, cutting the bar longitudinally along its central portion a distance equal to the width of the commutator bar to be produced less the width of the said tang, cutting the bar at right angles to its length from the termination of the said central longitudinal cut to the edge opposite the predetermined edge first referred to, cutting the bar at right angles to its length and throughout its entire width at a distance from the last-named cut substan-

tially equal to the width of the tang of the commutator bar to be produced, removing spaced wedge-shaped portions from the opposite edges of said strip at corners adjacent the respective cuts described to form keystone shaped parts at the opposite edges, said parts tapering in thickness toward their longitudinally wider portions.

2. The method of manufacturing commutator bars consisting in forming suitable material into a relatively thin wide strip having a central plane portion with opposite sides substantially parallel and opposite side portions having their opposite walls converging outwardly, cutting the bar at substantially right angles to its length from a predetermined edge to substantially the central portion of the bar and along a line located at a distance from the end of the bar substantially equal to the width of the tang of the commutator bar to be produced, cutting the bar longitudinally along its central portion a distance equal to the width of the commutator bar to be produced less the width of the said tang, cutting the bar at right angles to its length from the termination of the said central longitudinal cut to the edge opposite the predetermined edge first referred to, cutting the bar at right angles to its length and throughout its entire width at a distance from the last named cut substantially equal to the width of the tang of the commutator bar to be produced, removing spaced wedge-shaped portions from the opposite edges of said strip at corners adjacent the respective cuts described to form keystone shaped parts at the opposite edges, said parts tapering in thickness toward their longitudinally wider portions.

In witness whereof I have hereunto set my hand this 20th day of December, 1916.

ALBERT E. DOMAN.

Witnesses:
